UNITED STATES PATENT OFFICE.

JOHN H. H. McNAMEE, OF CAMBRIDGE, MASSACHUSETTS.

DESIGN FOR A BADGE OR BUTTON.

SPECIFICATION forming part of Design No. 28,502, dated April 26, 1898.

Application filed March 6, 1897. Serial No. 626,325. Term of patent 14 years.

To all whom it may concern:

Be it known that I, JOHN H. H. McNAMEE, a citizen of the United States, residing at Cambridge, in the county of Middlesex and State of Massachusetts, have invented and produced a new and original Design for a Society Badge or Button, of which the following is a specification, reference being had to the accompanying drawings.

Figure 1 is a plan view of a button which represents my design. Fig. 2 is a side elevation of the same.

A represents a badge or button, and upon its face are represented three caravels B,

which are shown in perspective and advancing in a straight line, the two rear caravels decreasing in size, as shown. The sail C of each caravel is shown as furled, and flying from the masthead D of each one is a flag G.

Having thus described my invention, I claim—

A design for a badge or button, substantially as shown and described.

JOHN H. H. McNAMEE.
